UNITED STATES PATENT OFFICE

EUGENE L. SCHELLENS, OF MILLBURN, NEW JERSEY, ASSIGNOR TO C-S ENGINEERING COMPANY, OF ENGLEWOOD, NEW JERSEY, A CORPORATION OF DELAWARE

METHOD OF AND APPARATUS FOR CLEANING FEED WATER HEATERS

Application filed September 7, 1928. Serial No. 304,591.

This invention involves a method of and apparatus for cleaning feed water heaters, and is particularly adapted to the cleaning of heaters of the closed or tubular type especially in locomotive service, since in such service the conditions of operation are severe, the quality of water varies greatly as the locomotive moves from place to place, and the expense and trouble of maintaining suitable cleaning equipment and crews at various points is almost prohibitive.

In bad water districts, particularly, the closed type of feed water heater has heretofore been at a great disadvantage, owing to the formation of scale on the water side of the tubes. In such districts, it is not unusual, in order to maintain the efficiency of the heater, to remove the scale as frequently as once a week. It has been heretofore necessary to supply and maintain, at each terminal, rather elaborate apparatus or equipment for this purpose.

It has also required considerable time to connect up the apparatus with the heater, and during the washing, which has heretofore usually required several hours, the locomotive is out of service and the workmen or attendants are frequently idle during that time. Costs are thereby multiplied.

In addition to the foregoing, if scale-encrusted heaters are not regularly cleaned, the losses in heat transfer resulting from the scale are so excessive that any attempt to equip a locomotive with the proper size of heater is largely nullified.

In general, it is the object of this invention to overcome these difficulties and disadvantages, and to do so in a very simple manner with the least complication of apparatus.

More specifically the invention contemplates a method and apparatus for cleaning feed water heaters which eliminates the necessity for equipment and costly cleaning crews at terminals; which reduces the time required to clean the heater; which utilizes the feed water system itself, as at present constructed and applied to locomotives, to clean the heater; which automatically clears out the acid or other cleaning compound at

the end of the cleaning process; and which renders cleaning an easy matter, at any time or place, by one man or attendant.

How the foregoing advantages, together with such others as are incident to the invention or will occur to those skilled in the art, are obtained by this invention, will be clear from the following description, taken together with the accompanying drawing which is a somewhat diagrammatic fragmentary side view of a locomotive embodying the apparatus of the present invention.

The drawing illustrates a locomotive having a boiler 2, a closed type feed water heater 3, a pump 4 which takes water from the tender (not shown) through pipe 5 and delivers it through pipe 6 to the heater, an outlet pipe 7 from the heater to the check valve 8 delivering into the water space of the boiler, an exhaust steam connection 9 from the valve chest 10 to the heater, a heater condensate drain 11, a live steam heating-pipe 12 having the usual valve 13 connected into the steam space of the boiler for warming the feed water system to prevent freezing when the engine is standing idle, and a drain cock 14 in the line 6 for permitting a circulation through the system from pipes 12 and 7 for warming purposes. A check valve 6a, located in pipe 6 between the pump 4 and the drain cock 14, prevents the pump from filling with steam in case of leakage of the main check valve 8.

While the invention may readily be employed in connection with other forms of heaters, the heater 3, here shown, with its water tubes 3a, is of the multi-tube semi-circular type, fully illustrated and described in the co-pending application of E. L. and C. A. Schellens, Serial No. 94,370, filed March 13, 1926, and assigned to the assignee of this present invention. Such heater has a plurality of passes of water tubes, connected serially, to the first pass of which the water flows from inlet pipe 6, and from the final pass of which the water passes into the outlet pipe 7 and thence to the boiler.

The present invention contemplates the employment of the warming system, or steam line 12, for carrying cleaning ma-

material through the heater and feed water system, preferably accomplished by the insertion of a chamber or tank 15, having a plug 16, in the live steam line 12 which delivers into pipe 7. This tank 15 is preferably a small one, for example, of about 2 or 3 quarts capacity, and may conveniently be mounted near the top of the boiler, as shown, above the high water level (indicated at 17).

When the locomotive comes in from a run, there is poured into the tank or reservoir 15, through the filling plug 16, about 1, 2 or 3 quarts of a concentrated cleaning solution, such, for example, as a fluid containing muriatic acid.

Drain cock 14 is then opened slightly, and steam heat valve 13 is opened, and the engine is so left until it is ready to go out.

The steam forces the solution from tank 15 through pipe 12 into the heater discharge line 7, the solution being diluted with the water therein. The condensing steam, produced by the radiation of this pipe 7, gradually causes the solution to work back through the heater tubes 3a, and thence, in a more and more diluted form, through pipe 6 to the drain cock 14. It is also evident that, in a heater having a plurality of passes of water tubes, the solution, while it is strongest, will work first through the final pass of tubes (where the scale is always the heaviest), and will become successively or progressively diluted as it works toward the first pass of water tubes (where the scale is least heavy), thus automatically providing approximately the proper strength for the several passes of tubes.

It will now be obvious that the invention does away with the necessity for any complicated apparatus, and makes the cleaning of the heater so simple that it can be accomplished with little labor and slight cost, at the end of each trip if necessary. In bad water districts whenever an engine comes in from a run there will be a small amount of scale in the heater tubes which, if immediately removed, presents no serious problem. It is, therefore, by this invention feasible to maintain the heater in a high state of efficiency instead of waiting until a large part of the normal feed water heating savings are sacrificed.

It will now further appear that the present invention, since it provides for the introduction of the solution into the heater at boiling temperature, greatly hastens the chemical action and reduces the time element required to dissolve a given amount of scale. Furthermore, since the solution enters the heater at the exit side where the scale is worst, it is strongest there, and becomes progressively diluted as it flows through to the inlet side, and, since condensate is continually added, from the steam

introduced, the solution is completely discharged after a brief period of operation and is displaced by distilled water, which washes the acid away from the metal surfaces and automatically eliminates the corrosion which would occur if the solution were allowed to remain in the heater.

In addition to the foregoing, the employment of the usual warming system outlet 14, which is at the discharge side of the pump 4, as a drain for the cleaning solution, prevents the entry thereof into the pump. The usual check valve 6a also serves the same end.

What is claimed as new is:

1. The method of cleaning a tubular feed water heater which consists in carrying a cleaning solution through the heater tubes from the outlet side of the heater to the inlet side and in diluting the solution by the carrying medium as it passes through the heater.

2. The method of cleaning a water-tube feed water heater having an anti-freeze or warming system, which consists in utilizing said warming system to carry a cleaner through the tubes of the heater.

3. The method of cleaning a boiler feed water system which consists in flowing steam into the system under the influence of condensation therein, in introducing a cleaner into the system with said steam, and in carrying the cleaner through said system in a direction reverse to the normal direction of flow.

4. The method of cleaning a boiler feed water system which consists in passing steam into the system adjacent the normal outlet side thereof, in introducing a cleaner into the system by means of said steam, in condensing the steam in said system, and in draining the condensate and cleaner from the system at the normal inlet side thereof.

5. The method of cleaning a locomotive boiler tubular feed water heater, which consists in introducing steam from the boiler into the heater tubes at the exit side of the heater, in introducing a cleaner therewith, and in draining off the mixture at the water inlet side of the heater.

6. The method of cleaning, a locomotive boiler tubular feed water heater, which consists in introducing steam from the boiler into the heater tubes at the exit side of the heater, in introducing a quantity of cleaning solution therewith, in continuing the introduction of steam after the introduction of the cleaning solution, and in flowing off, at the water inlet side of the heater, the solution introduced.

7. The method of cleaning a multi-tube liquid heater having the tubes in a plurality of passes, which consists in passing a cleaning solution through the tubes by introduc-

ing the same into the last pass first and thence successively through the other passes. 8. The method of cleaning a multi-tube liquid heater having the tubes in a plurality 5 of passes, which consists in passing a cleaning solution through the tubes by introducing the same into the last pass first and thence successively through the other passes, and in diluting the solution by its carrying 10 medium as it flows through the passes.

9. The method of cleaning a multi-tube liquid heater having the tubes in a plurality 15 of passes, which consists in passing a cleaning solution through the tubes by introducing the same into the last pass first and thence successively through the other passes, and in effecting said flow by steam.

10. In a closed feed water heater system 20 for boilers, the inclusion of means for introducing a cleaner into the water side of the system and means for flowing it therethrough under the influence of condensation in a direction opposite the normal direction of flow of the feed water, so that 25 the fresh cleaner contacts first with the dirtiest part of the system.

11. In a closed feed water heater system 30 for boilers, the inclusion of means for introducing a cleaner into the water side of the system and means for flowing it therethrough in a direction opposite the normal direction of flow of the feed water, so that 35 the fresh cleaner contacts first with the dirtiest part of the system, said latter means including a conduit and valve means for introducing steam from the boiler to a point in the system and a drain cock at another point in the system.

12. The combination, with a locomotive 40 having a boiler, a feed water system including a tubular heater, a water delivery line to the heater, and a water discharge line from heater to boiler, of means for passing a cleaning solution through the tubes of the 45 heater including means for introducing the solution into the heater on the side of the discharge line and means for discharging it therefrom on the side of the delivery line.

13. The combination, with a locomotive 50 having a boiler, a feed water system including a tubular heater, a water delivery line to the heater, and a water discharge line from heater to boiler, of means for 55 passing a cleaning solution through the tubes of the heater including a steam conduit from the boiler to the discharge line having a valve and a cleaning-solution reservoir therein, and a drain cock in said 60 delivery line.

14. In a locomotive, having a feed water system with a tubular water heater therein and a steam warming system connected to the water side of the feed water system, 65 means in the warming system for passing

a cleaning solution through the said water side of the heater.

15. In a locomotive, having a feed water system with a tubular water heater therein and a steam warming system connected to 70 the water side of the feed water system, means in the warming system for passing a cleaning solution through the said water side of the heater with the warming fluid.

16. In combination with a locomotive 75 having a boiler and a multi-tube multi-pass feed water heater, a water-inlet connection to the first pass of the heater, a water outlet connection from the last pass of the heater to the boiler, means for introducing a cleaning solution into the heater tubes through the outlet connection, and means for discharging said solution from the inlet connection.

17. In combination with a locomotive 80 having a boiler and a multi-tube multi-pass feed water heater, a water-inlet connection to the first pass of the heater, a water outlet connection from the last pass of the 85 heater to the boiler, means for introducing a cleaning solution into the heater tubes through the outlet connection, and means for discharging said solution from the inlet connection, said introducing means comprising a steam supply pipe with a cleaner 90 tank connected therein.

18. In combination with a locomotive and its boiler and feed water heater, a water delivery line to the heater, a water discharge 100 line from heater to boiler, a pump in said delivery line, means for flowing a cleaning solution from the discharge line through the heater and thence to the delivery line, and means preventing entry of the solution from 105 the delivery line into the pump.

In testimony whereof I have hereunto signed my name.
